Primary Examiner — Karen S Acker(74) *Attorney, Agent, or Firm* — Leason Ellis LLP(57) **CLAIM**

The ornamental design for a fabric with pattern, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a fabric with pattern according to a first embodiment of the claimed design;

FIG. 2 is an enlarged detail view of area 2 circumscribed within FIG. 1;

FIG. 3 is a front view of a fabric with pattern according to a second embodiment of the claimed design; and,

FIG. 4 is an enlarged detail view of area 4 circumscribed within FIG. 3.

The broken line surrounding FIGS. 2 and 4 and within FIGS. 1 and 3 denote the boundaries of the detail areas and form no part of the claimed design.

1 Claim, 4 Drawing Sheets
(4 of 4 Drawing Sheet(s) Filed in Color)
